PITCH CHANGING MECHANISM

Frank W. Caldwell and Eric Martin, West Hartford, Conn., and Edwin E. Vincent, Springfield, Mass., assignors to United Aircraft Corporation, East Hartford, Conn., a corporation of Delaware

Application January 15, 1941, Serial No. 374,440

4 Claims. (Cl. 176—163)

This invention relates to improvements in aeronautical propellers and has particular reference to an improved pitch changing mechanism for a controllable-pitch aeronautical propeller.

An object of the invention resides in the provision of an improved pitch changing mechanism of the character indicated of reduced weight and improved accuracy for constant-speed control.

A further object resides in the provision of an improved pitch changing mechanism of the character indicated which is completely and instantly reversible to change the propeller pitch in either direction regardless of centrifugal twisting moments and other forces acting on the propeller blades.

A still further object resides in the provision of an improved pitch changing mechanism of the character indicated which is highly stable in operation and is effective to maintain the propeller blades locked in adjusted position except when the mechanism is actuated to change the pitch position of the blades.

Other objects and advantages will be more particularly pointed out hereinafter or will become apparent as the description proceeds.

In the accompanying drawings, in which like reference numerals are utilized to designate similar parts throughout, there is illustrated a suitable mechanical arrangement for the purpose of disclosing the invention. It is to be understood, however, that the drawings are for the purpose of illustration only and are not to be taken as limiting or restricting the invention since it will be apparent to those skilled in the art that various changes in the illustrated arrangement may be resorted to without in any way exceeding the scope of the invention.

In the drawings,

Fig. 1 is a longitudinal sectional view through a pitch changing mechanism constructed according to the invention.

Fig. 2 is a longitudinal sectional view through the pitch changing motor shown in elevation in Fig. 1.

Fig. 3 is an end elevational view of the motor shown in Fig. 2 looking at the left hand end of the motor as shown in Fig. 2.

Fig. 4 is a transverse sectional view on the line 4—4 of Fig. 2 looking in the direction of the arrows.

Fig. 5 is a transverse sectional view on the line 5—5 of Fig. 2 looking in the direction of the arrows.

Fig. 6 is a transverse sectional view on the line

6—6 of Fig. 2 looking in the direction of the arrows.

Fig. 7 is a transverse sectional view similar to Fig. 4 showing the motor control valves in a different operative position from that illustrated in Fig. 4 and in the same operative position as is shown in Fig. 8.

Fig. 8 is a transverse sectional view similar to Fig. 5 showing the motor control valve in a different operative position from that illustrated in Fig. 5.

Fig. 9 is a longitudinal sectional view, similar to Fig. 2, of the left hand portion of the pitch changing motor taken on the line 9—9 of Fig. 3 and showing the motor control valve in the operative position shown in Fig. 5.

Fig. 10 is a longitudinal sectional view of the left-hand end of the pitch controlling motor similar to Fig. 9 and showing the motor controlling valve in the operative position shown in Fig. 8.

Fig. 11 is a front-elevational view of a portion of the reduction gear mechanism incorporated between the pitch changing motor shown in Fig. 2 and the propeller blades.

Fig. 12 is a transverse sectional view on the line 12—12 of Fig. 1 showing a blade pitch locking mechanism, and

Fig. 13 is a diagrammatic view of the propeller support and the oil line connections for leading hydraulic fluid to and away from the propeller.

Referring to the drawings in detail and particularly to Fig. 13, the propeller includes a hub member generally indicated at 18 in which are rotatably mounted a plurality of blades, one of which is generally indicated at 12, and a hub carried pitch changing mechanism, generally indicated at 14. The propeller is carried upon and driven by a propeller shaft 16 projecting from an engine 18 through a suitable bearing 20, the hub member 18 being secured on the shaft 16 by suitable means, such as locating cones one of which is indicated at 22, and a splined driving connection 24. Hydraulic fluid under pressure may be supplied to the pitch changing motor through a tubular conduit 26 disposed within the hollow drive shaft 16 and through the space between the tube 26 and the hollow drive shaft 16. The tube may be connected through a plug 28 in the drive shaft and oil transfer bearing 30 to a conduit 32 which may be connected to a valve 34 operated by a speed governor 36 and the space between the tube and the drive shaft may be connected to the valve 34 through a similar conduit 37. An engine driven pump 38 may be connected to the opposite side of the

valve 34 in such a manner that the valve will connect the outlet of the pump with one of the conduits 32 or 37 and the intake of the pump with the other conduit, the relation of the conduits to the pump outlet and intake being determined by the position of the plunger 46 of the valve 34 as controlled by the speed responsive governor 36.

With this arrangement the governor actuated valve 34 will operate to connect one side of the pitch changing motor with the pump outlet and the opposite side with the pump inlet in response to a governor demand for an increase in speed, and to reverse this connection in response to a governor demand for a decrease in speed.

Fluid for operating the propeller pitch changing mechanism under control of the governor may be contained entirely within the propeller hub, the pump 38 and the lines connecting these devices. If found desirable, a make up reservoir 39 may be connected with the pump through a suitable check valve in which case the operating fluid supply for the pitch changing mechanism would still be separate and independent of the engine lubricating oil supply, at least for governor controlled operation of the pitch changing mechanism.

A separate motor driven pump 41 may be provided for feathering and unfeathering the propeller. This pump may have its intake connected through a conduit 42 with the make up reservoir 39 or with the engine oil sump 43 and its outlet connected through a conduit 44 and pressure operated valve 45 with one of the conduits 32 or 37 leading to the pitch changing mechanism. In the illustration, the valve 45 is shown as having a plunger 46 urged by a compression spring 47 to a position in which it connects the conduits 32 and 37 with the valve 34 and blocks off the conduit 44. When the pump 41 is operated the plunger 46 will be moved by the fluid pressure exerted by this pump against the force of the spring 47 to a position in which it blocks off both conduits 32 and 37 from the valve 34 and connects the conduit 44 with the conduit 37 through the bypass channel 48. At the same time the channel conduit 32 will be connected with the drain conduit 213 to connect one side of the pitch changing motor with drain so that the motor may continue to operate in a pitch increasing direction until maximum high pitch of the propeller is reached.

At its end adjacent the pitch changing mechanism the tube 26 may project into a plug member 49 secured in the end of the drive shaft 16 by a nut 50 screw threaded into the end of the shaft and both the plug and the nut may be provided with apertures 51 connected with one side of the pitch changing motor and leading into the space between the conduit 26 and the interior of the shaft 16.

Referring now to Fig. 1, the motor, generally indicated at 52 and which will be later described in detail, is rigidly mounted in a sleeve 53 by suitable means, such as the radially inwardly projecting sleeve carried detents 54 disposed at one end of the sleeve 53 and inter-engaging with axially extending detents 55 on the adjacent end of the outer motor casing 56 and the nut 58 screw threaded into the end of the sleeve 53 opposite the detents 54 and bearing against the opposite end of the casing 56 to secure the motor against rotation and endwise movements relative to the cage. The casing 56 closely surrounds the working parts of the motor and is rigidly secured to

the remainder of the motor by suitable means, such as the screw threads 60 and locking pins 62. The sleeve 53 is provided at its forward end, that is, the right-hand end as viewed in Fig. 1, with an integral radial extension 64 the outer portion of which is secured to an annular support 66 in the form of a relatively heavy annular ring or cylinder secured at one end to the forward end of the hub 10 by suitable means, such as the annular nut 68 which is screw threaded into a flange 70 formed on the hub and is provided with an annular internal shoulder cooperating with an opposed external shoulder on the member 66. If desired, anti-friction elements 72 may be interposed between these shoulders to facilitate turning of the nut 68 relative to the member 66 and the nut may be locked in place by suitable means, such as the locking pins 74. The flange 64 is secured to the member 66 by means of a clamping nut 76 screw threaded into the open end of the member 66 and bearing against the outer edge of a reduction gear spider 78 which in turn bears against the member 64 and forces this member against the adjacent face of an annular gear member 80 which is provided with an external shoulder cooperating with an internal shoulder provided in the member 66 to limit assembly movement of the member 80 through the member 66, and with cooperating splines, as indicated at 82, which maintain the member 80 against rotation relative to the member 66. With this arrangement the motor supporting sleeve 53 is rigidly mounted in the support 66 and held against rotation relative to the support by suitable means such as dowel pins, not illustrated, between the member 80 and the flange 64. However, this sleeve may be further supported by extending it with a bearing fit into the main pitch changing gear 84 which gear is rigidly centered relative to the member 66 by means of the annular gear member 86 and the annular anti-friction bearings 88 and 89.

The motor is provided with a drive shaft 90 which projects into an anti-friction bearing 92 provided in a gear member 94 mounted on the shaft 90 and having a bearing support 96 in an axially offset portion 98 of the bearing spider 78 spaced outwardly from the remainder of the spider 78 along the axis of the shaft 90. The shaft 90 is tubular, as is particularly shown in Fig. 2, and at its outer end, opposite the motor 52, it is provided with diametrically opposite extensions, as indicated at 100 and 102. These extensions project through apertures, slightly larger than the extensions, provided in a transverse wall 104 of the gear member 94 and into a relatively fixed race member 106.

A cam 108 integral with the wall 104 lies within the race member 106 between the extensions 100 and 102. Movable elements, such as the balls 110, Fig. 12, are disposed between the cam 108 and the race 106 in the spaces between the projections 100 and 102 and are forced into wedging relation between the cam and the race member 65 by the compression springs 112, with the object that the gear is always locked against rotation relative to the relatively fixed member 106 except when the shaft 90 releases the balls 110 and rotates the gear relative to the member 106. Since 70 the gear 94 is directly connected through a reduction gear train with the propeller blades, the blades will be locked in position at all times except those times during which the pitch is actually being changed by the motor 52.

The gear 94 meshes with one or more spur

gears, two of which are indicated at 114 and 116. The axle of each spur gear is mounted at its ends in suitable anti-friction bearings carried in the axially spaced portions of the member 78 and at its end opposite the portion 88 is provided with a relatively small gear, as indicated at 118 and 120, which small gears mesh with the teeth of an internally toothed ring gear 122 fixed to one end of a cage, generally indicated at 124, rotatably supported at each end upon the sleeve 53 by the annular anti-friction bearings 126 and 128.

The cage 124 carries one or more axles, as indicated at 130 and 132, and upon each axle there is mounted a double planet gear, as indicated at 134 and 136, respectively, in Fig. 1. One portion of each of the double planet gears meshes with the teeth of the internally toothed ring gear 80 which is fixed in the supporting ring 66 and the other portion of each planet gear meshes with the teeth of the internally toothed ring gear 86 which is rotatably supported in the support ring 66 by the annular anti-friction bearings 88 and 90 and fixed to the gear 84 against rotation relative thereto. The two ring gears 80 and 86 are of substantially the same diameter but one of them has a slightly less number of teeth than the other. For example, if a very high gear reduction is desired, one of the ring gears may have one tooth less than the other ring gear while both parts of each planet gear have exactly the same number of teeth. With this arrangement when a planet gear has completely circled the fixed ring gear the movable ring gear will have moved a distance of one tooth in one direction or the other and the reduction ratio will be one ring gear tooth for each revolution of the cage 124. With the additional reduction provided between the gear 84 and the gears 116 and 114 and the relatively high reduction between the gears 118 and 120 and the ring gear 122, it is apparent that an extremely high ratio can be obtained between the motor shaft 90 and the bevel gear 84.

Any number of planet gears may be used as may be necessary or convenient, the present arrangement, as particularly illustrated in Fig. 11, showing six double planet gears equally spaced about the cage 124. This fixture also shows that the two portions of all but one of the planet gears are angularly offset relative to each other to accommodate the teeth of the planet gears to the teeth of the ring gears with which they respectively mesh since the teeth of the ring gears will be correspondingly offset due to the fact that the two ring gears do not have the same number of teeth. As is particularly shown in Fig. 11, numbering the planet gears from 0 to 5 in a clockwise direction, gear number 1 has the teeth of its two portions slightly offset, gear number 2 has the teeth of the two portions further offset and gear number 3 has the maximum offset between the teeth of the two portions. From gear number 3 the offset is gradually reduced in the same rotational direction through gears number 4 and number 5 reaching a condition of no offset at gear numbered 0.

The movable ring gear 86 is operatively connected with the bevel gear 84 by suitable means, such as the spline connection 140, and the gear 84 meshes with all of the propeller blade turning gears, one of which is indicated at 142 in Fig. 13 so that, whenever the gear 84 is rotated all of the propeller blades are rotated simultaneously and coextensively to change the pitch setting of the propeller.

Suitable pitch limit stop means in the form of

5 a pair of rings 143 and 144 having properly spaced radial offsets may be provided to limit the rotation of the gears 84 and 86 in both directions and thereby limit the total pitch varying range of the propeller blades. These rings may be set into an annular member 146 disposed between the end of the hub 10 and the adjacent end of the support ring 66 and secured to the ring by suitable means, such as the screws 147. The rings may be held against rotation relative to the member 146 by suitable intermeshing teeth 148.

10 One or more tapered pins, as indicated at 150, having one end set into the hub 10 and the other end received in a wall in the member 66 may be provided for properly locating the member 66 during assembly and for resisting rotation of the member 66 relative to the hub member under the torque loads imposed by the pitch changing mechanism.

15 Suitable channels, as indicated at 152 and 154 may be provided for the introduction of lubricant into the hub to lubricate the various elements of the pitch changing mechanism. These channels are disposed at diametrically opposite sides of the hub and are not connected but open into the hub 20 at the point at which it is desired to maintain the level of lubricant in the hub. When it is desired to introduce lubricant into the hub the hub is positioned with one channel near the top and the other near the bottom. Both of the screw plugs 156 and 157 are then removed and lubricant is poured into the top channel until it begins to run out of the bottom channel. The proper amount of lubricant will then be in the hub and the plugs 156 and 157 will be replaced to prevent loss of lubricant through these channels. Whenever the pitch changing mechanism operates the lubricant is carried by the planet gears to the central gears and the various bearings. The front end of the pitch changing mechanism may be enclosed by a suitable cover member or dome 158 which may be secured in place by an annular nut 160 rigidly secured thereto. The dome and nut may be rotated by suitable tools inserted in tapped holes such as indicated at 162.

25 It is to be noted that the entire pitch changing mechanism including the motor, the reduction gear unit, the support and the cover member can be pre-assembled to constitute a complete unit bodily removable from the propeller hub and that this unit may be easily assembled with the propeller hub by locating the support ring 66 with the pins 150 and turning the nut 68 into operative position and locking it in place. This greatly facilitates propeller construction since the pitch changing unit can be bench assembled and tested and adjusted before assembly with the propeller and is also of great convenience in service since the pitch changing mechanism can be bodily removed from the propeller and replaced by a different complete unit and can then be overhauled separately from the remainder of the propeller.

30 Referring now particularly to Fig. 2, the motor 52 comprises, in general, a cylinder block 164, the sleeve member 56, a valve mechanism 166, a plurality of pistons 168 connected to a wobble plate 170 mounted on the motor shaft 90 by an anti-friction bearing 172; an annular bearing support 174, and a fluid seal 176 between the shaft 90 and the adjacent end of the member 56 and shaft bearing 177.

35 The cylinder block 164 is provided with a central bore 178 within which the valve mechanism 166 is rotatably disposed, and with a plurality of

cylinder bores, one of which is indicated at 180, within each of which there is disposed a reciprocable tubular piston, as indicated at 168. At its end opposite the opened ends of the cylinder bores 180 the block 164 is provided with a cylindrical portion 182 which forms a seal fit with a larger diameter portion 184 (Fig. 13) of the nut 50 screw threaded into the end of the shaft 16, and with a smaller cylindrical portion 186 which forms a seal with a smaller diameter portion 187 of the nut. The apertures 51 are between the larger and smaller portions 184 and 187 of the nut 50. A plurality of connecting ports or apertures, as indicated at 188, which open into an annular groove 190 surrounding and communicating with the central bore 178 are disposed between the cylindrical portions 182 and 186 of the block 164. Each of the cylinders 180 has at its closed end a port 192 opening to the central bore 178.

The valve mechanism 166 comprises a rotatable plug member 193 having a closed outer end and two longitudinal channels 194 and 195 separated by a longitudinal partition 196 all rigidly secured in a rotatable sleeve 198. The channel 194 opens to the end of the plug member adjacent the end of the tube 26 and connects with the end of the tube so that hydraulic fluid under pressure in the tube may flow into the channel 194. This channel also extends over the cylinder ports 192. The channel 195 extends over the cylinder ports 192 and the annular groove 190. Surrounding the plug member 193 is the sleeve member 198 rigidly secured to the plug member by suitable means, such as the rivets 200, and provided with a hollow reduced extension 202 within which is disposed a fluid pressure actuated piston 204 and a compression spring 206 opposing movement of the piston away from the position illustrated in Fig. 2. The sleeve 198 is provided with an aperture 208 through which the channel 194 may communicate with the cylinder ports 192 and with a second aperture 210 of substantially the same extent as that of the channel 195 and overlying this channel. A tubular member 212 surrounds the sleeve member 198 and has a driving connection 214 with the inner end of the hollow drive shaft 90 so that the tubular member and the valve mechanism will rotate with the shaft.

From an inspection of Fig. 5 it is apparent that the channel 194 will always be in communication with at least one of the cylinder ports 192 so that pressure fluid may flow from the tube 26 to the closed end of the respective cylinder through this channel or alternatively exhaust fluid may flow from the cylinder to the tube and pump intake. When the high pressure fluid is supplied through the tube 26 the direction of rotation of the plug 193 and sleeve 198 is such that the channel 194 is first connected with each cylinder while the respective piston is at or near the closed end of the cylinder so that fluid flowing into the cylinder will tend to force the piston outwardly. As each piston is forced outwardly it exerts a force on the wobble plate 170 tending to cause the wobble plate to assume a different angular position with respect to the axis of the shaft 90. Since the wobble plate is mounted on the shaft 90 by means of the antifriction bearing 172 disposed at an angle to the axis of the shaft 90, the force exerted on the wobble plate by the piston 168 will cause the shaft to rotate about its axis in a manner well known to the art. As the shaft 90 rotates under the force exerted on it by the piston 168 through the wobble plate 170 it carries

the outer sleeve member 212, the inner sleeve member 198 and the valve plug 193 with it so that the channels 194 and 195 in the valve plug are brought successively into communication with the lower ends of the cylinders 180 to apply hydraulic fluid under pressure to the inner ends of the pistons which occupy a retracted position in their respective cylinders and connect with drain the inner ends of those cylinders whose pistons occupy a projected position.

When the governor controlled valve 34 is in position to supply the hydraulic fluid under pressure through the space between the tube 26 and shaft 16 the channel 195 will be connected with the cylinders in which the pistons are moving outwardly while the channel 194 will be connected with the cylinders in which the pistons are moving inwardly. With this arrangement the hydraulic fluid under pressure may be supplied either through the conduit 26 or through the space between this conduit and the hollow shaft 16 and the alternative channel will be vented to drain depending upon the position of the governor valve. When the pressure fluid is supplied through the channel 194 and the channel 195 is connected with drain, the motor will rotate in one direction, and when the channel 194 is connected with drain and the channel 195 connected with the source of hydraulic fluid under pressure, the motor will rotate in the opposite direction. As is particularly shown in Figs. 5 and 8, each channel (194 or 195) is connected at all times with four of the nine cylinders shown, only one cylinder being blocked off at any one time, this being the cylinder which has its piston in top or bottom dead center position at the particular time and is thus in process of changing from intake to exhaust. Thus, each channel is open to each respective cylinder for a time interval corresponding to slightly less than one hundred and eighty degrees of shaft rotation which corresponds to a piston movement from fully retracted position to the top dead center position or vice versa. It is thus seen that the motor will operate with equal facility in either direction depending upon which channel supplies the fluid under pressure and which is vented to drain.

As long as the pitch changing mechanism is operating under governor control, it will limit the range of pitch angles to the range necessary to maintain the propeller speed substantially at the speed for which the governor is set. This means that if the engine power is sufficiently reduced the propeller would go to its limiting low pitch position as determined by the low pitch stop comprising one of the rings 143 and 144. If the proper propeller is mounted on the engine, however, it will absorb the maximum power output of the engine at a high pitch setting at which the blades still maintain the major portion of their propulsive efficiency and the speed control will not, therefore, increase the pitch beyond this maximum pitch angle during constant speed operation.

If it is desired to change the propeller pitch beyond the constant-speed range to a feathered condition, the feathering pump 41 is put into operation. As this pump builds up a pressure above the pressure produced by the engine driven pump 38, this higher pressure will act on the valve 45 to cut off the governor from the lines 32 and 37 and connect the feathering pump through the line 37 with the valve channel 195. Hydraulic fluid from the pump 41 entering the

channel 193 will operate the motor 52 and continue its operation until a maximum pitch or feathered condition of the propeller is reached the channel 194 being connected with drain through the conduit 213. If desired, the operation of the pump may be discontinued at this point by some suitable device such as a pressure relief switch 215 one form of which is particularly illustrated and described in United States Patent No. 2,333,973, issued November 9, 1943, by Murray C. Beebe, Jr., for Electric feathering control. With this arrangement the propeller blades would be turned to their high pitch or feathered position and left in that position with the pump 41 and motor 52 idle until actuated to return the propeller from its feathered condition.

When it is desired to unfeather the propeller, that is, to return the propeller from its feathered position to the constant-speed control range of pitch angles, operation of the pump 41 may be resumed as by reactuating the pressure cut-out switch 215 or operating a different switch set for a higher pressure so that hydraulic fluid at an increased pressure will be supplied to the channel 195. As the propeller pitch changing mechanism cannot move further in the pitch increasing direction because of the operation of the positive high pitch limit stop, pressure will build up in the channel 195 and below the piston 204 through the port 216. When this pressure reaches a predetermined value the spring 206 will collapse permitting the piston 204 to move from the position shown in Figs. 2 and 9 to the position shown in Fig. 10. As the piston moves it carries with it a pin 218 which moves in cam slots 220 in the sleeve 198 and in grooves 222 in the outer sleeve member 212 thereby causing a rotation of the sleeve 198 and plug 193 relative to the outer sleeve 212 and bringing the valve channels from the position shown in Figs. 4 and 5 to the position shown in Figs. 7 and 8 thereby reversing the application of hydraulic fluid under pressure and the connection of the drain channel to the motor 52 and consequently reversing the direction of rotation of the motor shaft 90. The motor will then operate under the application of this high pressure fluid to move the propeller blades towards their low pitch position. Operation of the pump 41 may be manually discontinued when the blades reach the constant speed range of pitch angles or may be continued until the propeller has reached the position determined by the positive low pitch limit stop and the pressure exerted by the pump 41 has increased sufficiently to again trip the pressure operated switch and automatically discontinue operation of the pump and return control of the pitch changing mechanism to the governor 36 and pump 38.

The wobble plate member 110 and the pistons 168 are both provided with corresponding respective hook elements as well as with abutting surfaces at the ends of the pistons so that the pistons are secured to the wobble plate member against movement in both directions. This arrangement provides for an improved distribution of the forces exerted by the pistons on the wobble plate member since the pistons can be made to act in both directions by filling the space surrounding the wobble plate member with hydraulic fluid retained therein by the fluid seal 176 and also obviates the necessity of providing a fluid drain for the wobble plate chamber to take care of leakage past the pistons. With this arrangement, when one of the pistons is forced outwardly into the space by hy-

draulic pressure in the closed end of the respective cylinder this piston will displace fluid in the space surrounding the wobble plate member and this displaced fluid will act to drive back into their cylinders those pistons whose cylinders are exhausting at the particular time. Thus, the pistons act in both directions on the wobble plate member and power is derived from the pistons on the exhaust side of the motor as well as from the pistons on the pressure intake side at any particular time. The fluid in the space surrounding the wobble plate member also serves to lubricate the wobble plate bearing 172 and the shaft main bearing 177 as well as the connections between the various pistons and the wobble plate. Escape of this fluid through the shaft 90 is prevented by a partition 224 at the outer end of the shaft which location of the partition provides for the adequate lubrication of the valve mechanism.

While a particular mechanical arrangement has been illustrated in the accompanying drawings and hereinabove described for the purpose of disclosing the invention, it is to be understood that the invention is not limited to the particular construction so illustrated and described, but that such changes in the size, shape and arrangements of the various parts may be resorted to as come within the scope of the subjoined claims.

Having now described the invention so that others skilled in the art may clearly understand the same, what it is desired to secure by Letters Patent is as follows:

1. In a hydro-controllable feathering-type propeller, a hub, a blade mounted in said hub for pitch changing movements, a reversible multi-cylinder fluid motor in said hub, and a reduction gear train between said motor and said blade, said motor having a plurality of cylinders arranged in a circle, a piston reciprocable in each cylinder, a motor shaft, a wobble plate on said shaft connected with said pistons, a movable valve mechanism for directing the application of hydraulic fluid to the ends of successive pistons as said motor shaft is rotated, and pressure responsive means positioning said valve mechanism and operative to change the position of said valve mechanism and thereby reverse the direction of rotation of said motor shaft when subjected to a fluid pressure above a predetermined value.

2. The arrangement as set forth in claim 1 in which said valve mechanism is rotated by said motor shaft and said pressure responsive means comprises a piston and cam device between said valve mechanism and said shaft and a spring resiliently resisting the effect of fluid pressure on said piston.

3. In combination with a hydro-controllable feathering-type propeller, having a hub, a plurality of blades mounted in said hub for pitch changing movements, a multi-cylinder reversible fluid motor in said hub, a reduction gear train operatively connecting said motor with said blades to vary the pitch thereof, a rotatable valve in said motor for distributing fluid under pressure to the cylinders thereof and providing for the exhaust of fluid from said cylinders, said valve having two fluid passages either of which may either conduct fluid under pressure or exhaust fluid, speed responsive means for selecting the passage conducting pressure fluid and the passage conducting exhaust fluid to control the direction of rotation of said motor, manually controllable means for blocking off said speed responsive means and supplying hydraulic fluid to one of said passages until said propeller has been brought

to its feathered condition, and pressure responsive means associated with said valve for changing the relative position of said valve passages and said cylinders to reverse the direction of rotation of said motor to a pitch reducing direction upon further application of pressure fluid to said motor through said one passage after said feathered condition has been attained.

4. A controllable-pitch propeller having a reversible hydraulically operated pitch changing motor, and two hydraulic lines for supplying hydraulic fluid under pressure to one side or the other of said motor to operate it in one direction or the other, a governor actuated valve for selecting the line through which pressure fluid is supplied to said motor, a first source of fluid under pressure connected with said governor actuated

5 10 15 valve, a second source of fluid under pressure, a valve located between said propeller, said governor and said second source of fluid under pressure for disconnecting said governor from said propeller and connecting said second source of fluid under pressure with one of said hydraulic lines, and a fluid pressure actuated valve associated with said pitch changing motor operative by pressure developed by said second source of fluid under pressure in excess of a predetermined value to change the connection between said one hydraulic line and said motor to reverse the direction in which said motor is operated by pressure fluid supplied through said one line.
